UNITED STATES PATENT OFFICE.

FLOYD E. SHANNON, OF AKRON, OHIO.

DESIGN FOR AN ELASTIC VEHICLE-TIRE.

55,091.

Specification for Design.

Patented May 4, 1920.

Application filed December 12, 1919. Serial No. 344,492. Term of patent 14 years.

To all whom it may concern:

Be it known that I, FLOYD E. SHANNON, a citizen of the United States, residing at Akron, in the county of Summit and State of Ohio, have invented a new, original, and ornamental Design for Elastic Vehicle-Tires, of which the following is a specification; reference being had to the accompanying drawings, forming a part thereof.

Figure 1 is a plan view of a portion of an elastic vehicle tire, showing my new design, and,

Fig. 2 is a transverse sectional view of same.

I claim:

The ornamental design for an elastic vehicle tire as shown.

FLOYD E. SHANNON.
